[57] CLAIM

The ornamental design for an electrical ground lug, as shown and described.

DESCRIPTION

FIG. 1 is a top perspective view of an electrical ground lug showing my new design;

FIG. 2 is a front elevational view thereof, the rear elevational view being identical thereto;

FIG. 3 is a side elevational view thereof;

FIG. 4 is a top plan view thereof;

FIG. 5 is a bottom plan view thereof;

FIG. 6 is a top perspective view of an electrical ground lug showing a second embodiment of my new design, the top plan view thereof being identical to FIG 4;

FIG. 7 is a front elevational view thereof, the rear elevational view being identical thereof;

FIG. 8 is a side elevational view thereof; and,

FIG. 9 is a bottom plan view thereof.
